UNITED STATES PATENT OFFICE

2,141,906

BAG

Philip M. Friedlander, Brooklyn, N. Y., assignor
to Bertha Friedlander, Brooklyn, N. Y.

Application April 22, 1937, Serial No. 138,353

1 Claim. (Cl. 150—52)

My invention relates to bags and while I do not wish to limit the same to any particular use, I have shown my invention embodied in the types of bags commonly used for carrying a plurality of folding chairs. It is common for undertakers and others to use canvas and cloth bags for protecting and for carrying folding chairs, and I have shown in the drawing a bag of the type so used in carrying a group of folding chairs.

10 The principal object of my invention is to provide a simple and convenient method of closing the open side of a bag and for holding the flaps in closed condition while the bag is being carried. In one form of the invention I have shown four flaps at the open side of the bag, one flap projecting from each of the four sides of the bag. One of these flaps is provided with a loop and the other flaps are provided with openings therethrough and through these openings 20 the loop referred to is adapted to be passed in successive order as the several flaps are folded into closed position so that when all four flaps have been folded into closed position the loop referred to, which is attached to the lower flap of the set, will project above the topmost flap and through this extended portion of the loop the exterior strap which is passed around the entire bag is passed so that the outside strap cooperates with the loop and holds all of the flaps 30 neatly in their closed position.

In another form of my invention I have shown only two flaps adapted to lie in overlapping positions and the loop is connected with one of these flaps and passes through an aperture of the other flap in order to interlock the flaps and to permit the outside carrying strap to be passed through the loop.

The features shown in my Letters Patent No. 1,951,604 may be combined with the new features 40 of my present case if desired. Other features will be apparent from the following detailed description of my invention.

In the drawing forming part of this application,

45 Figure 1 is a plan view of the bag embodying my invention with the parts all shown in closed position,

Figure 2 is a sectional view taken on the line 2—2 of Figure 1,

50 Figure 3 is a plan view of the bag in open position ready to receive the folding chairs or other articles which are to be carried,

Figure 4 is a sectional view taken on the line 4—4 of Figure 3,

Figure 5 is an end view of the bag while in open position,

Figure 6 is an elevation of a bag showing my invention in a modified form,

Figure 7 is a plan view thereof with the bag in 5 open position,

Figure 8 is a similar view with the bag in closed position,

Figure 9 is a plan view of a buckle to be used 10 on the strap,

Figure 10 is an elevation thereof, and

Figure 11 is a perspective view of the movable middle pin of the buckle.

I will first describe the bag made according to Figures 1 to 5 inclusive. In this construction the bag includes opposed side walls 1, opposed end walls 2, a bottom 3 and the flaps to be described, for closing the top of the bag. While the bag illustrated is oblong in cross section it will be understood that it may be made square or any other shape. In this combination, as illustrated, there are two flaps 4, 5 contiguous with the two side walls of the bag and there are two flaps 6, 7 contiguous with the two end walls of the bag. Preferably, there is a continuous piece of tape 8 25 binding all the edges of all four flaps as a reinforcement to prevent tearing of the material especially at the meeting corners of the flaps.

One of the flaps is provided with a loop 9 and it may be any one of the four flaps. I have 30 shown a loop 9 attached to the end flap 6. The other three flaps are provided with means to interlock with this loop and this preferably consists of an aperture 10 through each of the flaps 4, 5, 7 through which the loop may be passed. 35

There is an outside strap 11 having a buckle 12 and this strap passes outside the bag around the ends, the bottom and the top of the bag. This strap passes through any number of loops 13 on the end and bottom walls of the bag which 40 keep the strap in place.

The buckle shown in Figures 9 to 11 may be used for tightening the strap 11 around the buckle. This buckle is of simple construction and it permits the strap 11 to be tightened around the bag very quickly; it is adapted to hold the strap firmly, and it may be very easily and quickly released. The strap 11 is provided with a loop 40 on one end which engages around one of the cross bars 41 of the buckle frame 42. This buckle frame consists of two side bars 43 shown arranged parallel to each other with the cross bar 41 arranged at one end of the side frames and with another cross bar 44 arranged at the opposite end of the frame and parallel with the 45 50 55

bar 41. The bar or pin 45 shown in perspective in Figure 11 has two flattened pintles 46 one on each end, which pintles extend into the slots 47 in the side bars 43. These pintles prevent the bar 45 from revolving and they are themselves 5 slidable in the slots 47 so that the bar 45 which lies parallel with the bars 41 and 44 is adapted to move laterally between the bars 41 and 44.

As stated above, one end of the strap 11 has a 10 loop 40 engaging around the bar 41 so that one end of the strap is thus anchored to this bar. There is a short strap 48 having one end looped at 49 around the bar 44. The free end of the strap 11, i. e., the end opposite to that having the 15 loop 40, after the strap is passed around the bag, has its free end pass upwardly between the frame members 43 and between the loop 40 and the cross bar 45. The free end of the strap is then 20 passed downwardly in the space between the cross bar 45 and the loop 49 of the short strap 48.

To tighten the strap 11 around the bag, the 25 free end 50 of the strap is drawn toward the left in Figure 10, which will cause the strap 11 to tighten around the bag. When the pull on the free end 50 of the strap is released, the tension 30 on the left hand portion of the strap 11 in Figures 9 and 10 causes the rod 45 to be pulled to the left in these views so that the end 50 of the strap 11 is crowded against the loop 49 of the short strap 48 which is itself crowded against the bar 44 so that the loop 51 is locked.

The pintles 46 are flattened so that the bar 49 cannot revolve or, in other words, act as a 35 roller. As the loop 51 is thus locked, the strap 11 remains tight around the package. To release the buckle, the free end of the short strap 48 is grasped in the hand and is moved upwardly in Figure 10. This causes the buckle to rock 40 from the bar 41 so that the pressure of the bar 45 toward the bar 44 is released and this allows the loop 51 to slide or move about the bar 45 so that the end 50 will pull out from between the bar 45 and the bar 44 and thus release the free 45 end of the strap.

This type of buckle needs no prongs or other members piercing the strap and causing it to wear; the strap may be tightened to any particular point, and the buckle is quickly and easily 50 released by simply lifting the short strap 48.

Operation

After the articles which are to be carried in the bag have been placed therein, the bag is 55 closed in the following manner: First the flap 6 which has the loop 9 is folded across the open end of the bag, as shown in Figure 2. Then the end flap 7 is folded across the open end of the bag and the loop 9 is passed through the aperture 60 10 in the flap 7. Then the side flap 4 may be folded across the open end of the bag and across the flaps 6 and 7, and the loop 9 is passed through the aperture 10 in the flap 4 which now registers with the aperture 10 of the flap 7. The flap 5 is 65 then folded across the open end of the bag and the loop 9 is passed through the aperture 10 of the flap 5 so that the parts are arranged in the position shown in Figures 1 and 2. The loop 9 which is attached to the lowermost flap passes 70 successively through the apertures 10 of the flaps 7, 4 and 5 and the loop projects above the flap 5. One end of the outer strap 11 is now passed through the protruding portion of the loop 9 and this is then attached to the buckle end of the strap and the strap is drawn tight and the buckle 75

closed. The whole bag with its contents may be carried by grasping the strap 11, preferably between the adjacent loops 13 shown in Figure 5.

It will be apparent that even if the bag should be inverted the contents cannot fall out because 5 all the flaps are locked together by the loop 9 and the latter is held by the strap 11. In other words, the flaps are all retained in their folded positions regardless of any position the bag may assume. 10

As stated above, the bag may be provided with vertical dividing walls 15 forming separate compartments 16 for the reception of individual folded chairs, so that the latter will not rub directly against each other. If desired, the upper 15 edges of these partitions may be provided with apertures through which the strap 17, having one end attached to one of the side walls of the bag, may be passed through the openings in the partitions and united with another strap 18 having one end attached to the opposite side of the bag. These straps, therefore, will prevent the partitions 15 from sagging, thereby preventing the chairs in the compartments 16 from rubbing against each other. 20 25

In Figures 6 to 8 I have shown a modified construction of the bag wherein there are two parallel side walls 19 connected together by end walls 20 and I have shown vertical walls 21 forming pockets 22 to receive individual folded chairs. In 30 this form of the invention the side and end walls are carried the full depth of the bag but there are slots 23 extending downwardly from the open end of the bag to define the two flaps 24, 25 contiguous to the front and rear walls of the bag. 35 One of these flaps 25 is provided with a loop 26 corresponding with the loop 9 in the previous construction and when this flap is folded over across the open end of the bag the loop 26 is passed through an aperture 27 in the flap 24 to 40 attach these flaps together. In this form of the invention the outside strap 28 which passes through suitable loops 29 attached to the side walls of the bag has one end which is passed through the loop 26 after the flaps are folded 45 and then the ends of the outer strap are united by means of the buckle 30 and the strap is drawn tight. 50

It will be apparent that if folded chairs are placed in the bag with the lower ends of the legs 55 protruding into the extensions 31 that the flaps 24, 25 are folded across the end of the seat portion of the chairs and between the legs, or in other words, the flaps are not folded at the extreme outer end of the bag but in a line within 60 the contour of the bag. Preferably, the loops 29 are extended laterally across the bag as shown in Figure 6 and formed into loops 32 to constitute a handle by which the bag and its contents 65 may be carried. This construction is the same 70 at both sides of the bag.

It will be seen that I have provided a bag having flaps adapted to be overlapped at the open side of the bag for the purpose of closing the bag 65 and protecting its contents and that these flaps are interlocked and held by the outer or carrying strap so that the flaps are positively retained in their correct positions while the bag is being carried. 70

Having described my invention, what I claim is:

In a bag, a body including side walls defining an oblong structure in cross section, the side walls at one end being folded upon themselves 75

and secured in said condition to constitute a closed bottom end of the bag and open at the opposite end, the side walls of the body extending beyond the open end and arranged as closure flaps adapted to be folded inwardly into overlapped relation across and close the open end, one flap to constitute the lowermost flap in the folded condition of the flaps having a loop attached thereto, the other flaps having apertures corresponding to and through which the loop is adapted to be passed, short straps attached at the opposite ends in spaced relation to the ex-

terior of the opposite sides of the body to extend transversely thereof intermediate the ends of the body to form loops and the intermediate portion of said short straps projecting from a side of the body to constitute hand grips, and a long strap longitudinally encircling the exterior of the body passing between the body and the loops formed by the short straps and passing through the flap loop above the flaps to secure the bag parts together and articles in the bag. 5

10

PHILIP M. FRIEDLANDER.
